ATTORNEY.

UNITED STATES PATENT OFFICE

112,170

DESIGN FOR A NAVAL GAME BOARD

Lawrence E. Corser, Cortland, N. Y.

Application March 7, 1938, Serial No. 75,638

Term of patent 7 years

To whom it may concern:

Be it known that I, Lawrence E. Corser, a citizen of the United States, residing at Cortland, in the county of Cortland and State of New York, have invented a new, original, and ornamental Design for a Naval Game Board, of which the following is a specification, reference being had to the accompanying drawing, forming part thereof.

The figure is a top perspective view of a naval game board, showing my new design.

I claim:

The ornamental design for a naval game board, as shown.

LAWRENCE E. CORSER.
